(57) **CLAIM**

The ornamental design for a dog bowl as shown and described.

DESCRIPTION

FIG. 1 is a front, top and right side perspective view of a dog bowl, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged detail view of area 8 in FIG. 1.

The dashed broken lines illustrate portions of the dog bowl. FIGS. 1 and 8 show dash-dot broken lines that represent the boundaries and indicator of the enlarged views. The broken lines form no part of the claimed design.
